UNITED STATES PATENT OFFICE

2,146,568

BOILER LOW WATER CUT-OFF

John Eaton, Schenectady, N. Y., assignor to General Electric Company, a corporation of New York

Original application July 14, 1934, Serial No. 735,103. Divided and this application May 21, 1937, Serial No. 143,993

3 Claims. (Cl. 200—122)

This application is a division of my application, Serial No. 735,103, filed July 14, 1934, relating to automatic fuel burner control systems and apparatus.

5 The principal object of the present invention is to provide an improved form of boiler low water cutoff for preventing operation of the fuel burner for the boiler in case the boiler water level falls below a predetermined safe value, although 10 the device can be used in other service wherever it is desired to detect the presence and absence of a heat conducting fluid.

The improved form of fluid responsive cutoff of the present invention is of the electrically 15 heated thermostatic switch type and operates upon the principle that the heat generated by the electric heater is normally conducted into the boiler water or other fluid at a rate which maintains the thermostatic element below the 20 temperature value at which the switch is opened. Whenever there is no water or other fluid to carry away the heat, the thermostatic element then becomes effective to release the switch. In 25 accordance with the present invention, the thermostatic element is mounted at one end of an elongated member of heat conducting material having the other end thereof in heat conducting relation with the boiler water or other fluid. The 30 electric heater is mounted centrally on the heat conducting member and the heat is conducted principally to the other end thereof during the presence of the fluid in contact therewith, but flows to heat the thermostat at the other end of the elongated member during the absence of 35 fluid.

In the accompanying drawing, Fig. 1 is a sectional view of a preferred form of the improved boiler low water cutoff of the present invention; Fig. 2 is a front view showing the arrangement 10 of the switch mechanism and the terminal connection for the electric heater and for the circuit controlled by the cutoff, and Fig. 3 is a diagram illustrating the application of the cutoff to an electrically controlled fuel burner boiler.

45 As shown in Fig. 1 the low water cutoff consists of a tube 10 which is adapted to be mounted in an opening provided in the side of the boiler wall 11 at the minimum safe low water level line. As shown the internally threaded boss 12 is welded to the boiler walls 11 at 13 and the tube 10 is secured in position by means of the threaded collar 14 which engages with the threads in the boss 12. The collar 14 carries the circular plate 15 threaded thereon. The plate 16 which is secured to the open end of the tube 10 is clamped

to the plate 15 by means of the screws 17 with the packing rings 18 and 19 interposed between the end of the collar 14 and the plate 16. This provides a water-tight seal in the mounting of the tube 10 in the side of the boiler.

5 The tube 10 has a post 20 of heat conducting material mounted in the right-hand end thereof which is normally immersed in the water in the boiler by means of the mounting screw 21. A bimetallic thermostatic element 22 is 10 mounted at the free end of the post 20 and extends into latching relation with the cutout switch operating member 23.

As shown more clearly in Fig. 2, the cutout switch operating member 23 is provided with a 15 pair of spaced apart legs 23a which are pivotally mounted between the spaced apart posts 24 by means of the cotter pin 25. The movable switch member 23b, preferably a strip or bar of insulating material, is pivotally mounted between the 20 legs 23a on the cotter pin 25 and carries the movable switching contact 26 which is normally maintained in yielding engagement with the pair of spaced apart stationary contacts 27 by spring 28 as long as the bimetallic element 22 remains in 25 latching engagement with the switch operating member 23. The stationary contacts 27 are each mounted on a boss 27b extending from the base 27a which is formed preferably of moulded insulating material. The switch operating member 30 23 is normally biased to operate the movable switch member 23b to the circuit opening position by the spring 29.

Surrounding the post 20 is the electrical heater winding 30 which is provided with the two terminal connections 31 so that it may be connected 35 in circuit with the oil burner operating mechanism indicated diagrammatically in Fig. 3 by the reference character 32 for energization whenever the burner is in operation. It will be understood, however, that the heater winding 30 may 40 be energized continuously or in any desired manner in case the device is used to detect the presence and absence of liquid in other service.

In the boiler low water cutoff service illustrated in Fig. 3, the operation of the device is as follows: As long as the boiler water surrounds the tube 10, the heat generated by the heater winding 30 is conducted by the post 20 to the closed end of the tube 10 and thence into the 50 boiler water at a rate which maintains the temperature of the thermostatic element 22 below the value at which the switch operating member 23 is released. However, as soon as the boiler water level falls below that of the tube 10 in the 55

boiler, the heat accumulates in the post 20 and is transmitted to the thermal element 22 to raise the temperature of the latter. At a predetermined temperature the free end of the element 22 is moved to disengage the switch operating member 23 and permit the spring 29 to operate the bridging contact 26 to the circuit opening position. This disconnects all of oil burner mechanism and control apparatus from the supply line L₁ as indicated in Fig. 3. When the low water condition of the boiler has been corrected and the thermostatic element 22 has returned to normal temperature, the cutout switch mechanism may be reset into operating condition by manually pushing the upturned end 23c of the operating member 23 against the bias of spring 29 so as to reengage the upper end of the member 23 in latching relation with the thermal element 22.

In Fig. 3, electric power is supplied to the burner and control mechanism from the supply line L₁, L₂. The electric power supply circuit extends from supply line L₁ through the switch 33 which is opened whenever the flue door 34 opens due to excessive pressure in the combustion chamber of the boiler 11. The electric power supply circuit then extends through the contacts 27 and the movable switch member 26 of the low water cutout switch to the burner and control mechanism indicated diagrammatically at 32. This mechanism may be of any conventional type, although preferably of the type shown in my application, Serial No. 735,103, filed July 14, 1934. The burner and control mechanism are operated in the usual manner under the control of the room thermostat T and the heating coils 30 of the low water cutoff preferably is connected to be

energized only when the burner is in operation, although it may be energized continuously if desired.

What I claim as new and desire to secure by Letters Patent of the United States, is,—

1. A boiler low water safety device including a tube of heat conducting material having a closed end, means for mounting the tube at the low water line of the boiler, a post of heat conducting material mounted inside the tube in heat conductive relation with the closed end thereof, an electric coil for heating the post, control means mounted adjacent the open end of the tube, and a bimetallic thermostatic element mounted on the post for actuating said control means responsive to the rise in temperature of the post when the boiler water falls below said line.

2. In a fluid detector, the combination of a fluid contact member, a post of heat conducting material mounted in heat conducting relation therewith, an electric heater for heating the post, and a bimetallic thermostatic element mounted on the post for operation in response to the change in temperature thereof upon the presence and absence of fluid contact with said member.

3. In a fluid detector, the combination of an elongated member of heat conducting material having one end thereof in heat conductive relation with the fluid, electrical means for centrally heating said member, and a bimetallic thermostatic control member mounted in heat conductive relation with the other end of said member for operation in response to the change in temperature of said other end upon the presence and absence of the fluid heat conductive relation at said one end thereof.

JOHN EATON.
